UNITED STATES PATENT OFFICE.

HARRY A. WILSON, OF SALISBURY, MARYLAND.

DESIGN FOR A WOODEN ICE-CREAM SPOON.

53,548.

Specification for Design.

Patented July 8, 1919.

Application filed March 2, 1918. Serial No. 220,063. Term of patent 3½ years.

To all whom it may concern:

Be it known that I, HARRY A. WILSON, a citizen of the United States of America, residing at Salisbury, in the county of Wicomico and State of Maryland, have invented a new, original, and ornamental Design for Wooden Ice-Cream Spoons, of which the following is a specification, reference being had to the accompanying drawings, in which:

Figure 1 is a perspective view, drawn to

actual size, of a wooden ice cream spoon embodying my new design.

Fig. 2 is a plan view thereof, and

Fig. 3 is an edge elevation thereof.

I claim:

The ornamental design for a wooden ice cream spoon as shown.

HARRY A. WILSON.

Witnesses:

HOWARD H. RUARK,

E. C. AMES.
